UNITED STATES PATENT OFFICE.

HENRY J. ROBINSON AND THOMAS V. CONWAY, OF CLEVELAND, OHIO;
SAID CONWAY ASSIGNOR TO SAID ROBINSON.

PIPE-HANGER.

No. 802,087.

Specification of Letters Patent.

Patented Oct. 17, 1905.

Application filed July 23, 1904. Serial No. 217,782.

To all whom it may concern:

Be it known that we, HENRY J. ROBINSON and THOMAS V. CONWAY, citizens of the United States, and residents of Cleveland, county of 5 Cuyahoga, and State of Ohio, have invented a new and useful Improvement in Pipe-Hangers, of which the following is a specification, the principle of the invention being herein explained and the best mode in which we have 10 contemplated applying that principle so as to distinguish it from other inventions.

Our invention relates to pipe-hangers, and particularly to that class of hangers which is provided with an adjustable clamp, enabling 15 the hanger to be accommodated to supporting-beams of varying widths, and, further, which is vertically adjustable to enable the pipe to be supported at different heights, such vertical adjustment being secured without disconnecting the pipe from the hanger.

Furthermore, our improved hanger provides means for securing the pipe in a plane, cutting the plane of the supporting-clamp at any desired angle.

25 Said invention consists of means hereinafter fully described, and specifically pointed out in the claims.

The annexed drawings and the following description set forth in detail certain mechanism 30 embodying the invention, such disclosed means constituting but one of various mechanical forms in which the principle of the invention may be used.

In the annexed drawings, Figure 1 represents a front view of our improved hanger supported by a suitable I-beam, shown in broken section and holding a pipe, also shown in section. Fig. 2 represents a partial side elevation and a partial vertical section of the device 40 as illustrated in Fig. 1. Fig. 3 represents a horizontal section of the clamp forming a part of our invention, and Fig. 4 shows in perspective one of the component sections of said clamp.

45 Referring to the drawings, A represents a section of an I-beam, rail, girder, or other suitable means of support. A clamp B is adapted to engage said support and comprises two similar sections b b, adapted to be adjustable in a 50 horizontal plane, so as to accommodate said clamp to beams of varying widths. Said horizontal adjustability is obtained as follows: Each section b b comprises an arm b' and an end piece b², said arm being connected to said

end piece laterally of the center of the latter 55 about one-third of the distance from one edge, as shown in Figs. 3 and 4, and at about one-third of the distance from the other edge of said end piece b² is provided a slot b³ of substantially the same height and width as an arm 60 b' and through which the arm of the other section b is adapted to be passed, as shown in Figs. 1 and 3, and in which it is adapted to be supported, whereby the sections b b can be adjusted relatively to each other to enable the 65 clamp B to engage beams of varying widths, suitable hooks b⁴ being provided on the end pieces b² to grip over the flanges a a of the beam A. The sections b b having been adjusted as is desired may be fastened securely relatively to each other by means of a suitable screw b⁵ and a plurality of suitably-alined screw-holes b⁶.

The screw b⁵ is adapted not only to retain the sections b b securely relatively to each other, but also forms a support for a hanger-rod C, which is connected to the clamp B by means of a suitable cap c, through which is passed and against the under edge of which abuts a swivel-joint c', adapted at its outer 75 end to pass between the arms b' b' of the sections b b and provided with a suitable screw-hole registering with the screw-holes b⁶ of the arms b'. The lower end of the hanger-rod C is provided with the construction clearly 80 shown in Fig. 2, comprising the interiorly-threaded sleeve D, adapted at its upper end to engage the lower threaded end of the hanger-rod C and at its lower end to engage the exteriorly-threaded member E, provided with a 85 jam-nut e, adapted to screw up tight against the under surface of the sleeve D. It will be noted that by loosening up the nut e the construction shown and described enables the raising or lowering of the member E without 90 dismantling or disconnecting any parts of the device by simply turning the hanger-rod C in the proper direction. The member E is 95 adapted to receive and retain the two ears f f of a pipe-supporting band F, adapted to encircle and hold up a pipe G or any other object which it is desired to support.

In case it is desired to support a plurality of pipes G from one clamp B some of the hanger-rods C may be secured to said clamp 100 laterally of the central vertical plane passing through the beam A and either inside of or outside of the end pieces b².

It will be noted that the said construction gives a wide latitude to the widths of supporting-beams with which it may be readily and effectively connected and that after the connection with the pipe is made and secured the latter may be rotated through any arc and into a position at any desired angle relatively to the supporting-clamp and also adjusted vertically within the limits of movement of the member E within the sleeve D without disconnecting the beam or pipe from the hanger or any of the constituent parts of the latter from the other parts of the same.

Other modes of applying the principle of our invention may be employed instead of the one explained, change being made as regards the means herein disclosed, provided the means stated by any one of the following claims or the equivalent of such stated means be employed.

We therefore particularly point out and distinctly claim as our invention—

1. In a pipe-hanger, a clamp comprising two sections, each section comprising an arm and beam-engaging means and provided with a slot in which the arm of the other section

is adjustable; and means for fastening said sections together in any desired position.

2. In a pipe-hanger, a clamp comprising two sections, each section comprising an arm and a supporting member adapted to engage a beam and provided with a slot in which the arm of the other section is adjustable, whereby the distance between the supporting members may be varied; and means for fastening said sections together in any desired position.

3. In a pipe-hanger, a clamp comprising two similar sections, each section comprising an arm and a supporting member adapted to engage a beam and provided with a slot in which the arm of the other section is adjustably mounted, whereby the distance between the supporting members of the two sections may be varied; and means for fastening said sections together in any desired position.

Signed by us this 21st day of July, 1904.

HENRY J. ROBINSON.
THOMAS V. CONWAY.
